US00D913981S

(12) **United States Design Patent** (10) **Patent No.:** **US D913,981 S**
Kim (45) **Date of Patent:** **** Mar. 23, 2021**

(54) **TELEVISION SET**

(71) Applicant: **LG DISPLAY CO., LTD.**, Seoul (KR)

(72) Inventor: **InYoung Kim**, Paju-si (KR)

(73) Assignee: **LG DISPLAY CO., LTD.**, Seoul (KR)

(**) Term: **15 Years**

(21) Appl. No.: **29/687,697**

(22) Filed: **Apr. 15, 2019**

(30) **Foreign Application Priority Data**

Oct. 16, 2018 (KR) 30-2018-0047499

(51) **LOC (13) Cl.** **14-03**

(52) **U.S. Cl.**

USPC **D14/126**; D14/125

(58) **Field of Classification Search**

USPC D14/125-137, 239, 314-316; D6/300
CPC G06F 1/16; G06F 1/1601; G06F 1/1637;
G06F 3/041; G06F 3/0412; G06F 3/0416;
H04N 5/64; H05K 5/0204; H05K 5/0017;
H05K 5/0217; H04M 1/725; H04M
1/0202; H04M 1/0266

(57) **CLAIM**

The ornamental design for a television set, as shown and described.

DESCRIPTION

FIG. 1 is a front, right perspective view of the television set showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view showing the display in a rolled state.

1 Claim, 4 Drawing Sheets
